UNITED STATES PATENT OFFICE.

HARRY WAYNE WHITE, OF EMPORIA, KANSAS.

WASHING MACHINE.

Application filed October 8, 1921. Serial No. 506,358.

To all whom it may concern:

Be it known that I, HARRY W. WHITE, a citizen of the United States, and resident of Emporia, in the county of Lyon and State of Kansas, have invented certain new and useful Improvements in Washing Machines, of which the following is a specification.

This invention relates to washing machines and is an improvement on the construction illustrated in my United States Patent #1,378,925.

An important object is to provide a washing machine having a depending receptacle or container which constitutes a sediment collector and which is separated from the main washing chamber by means of a baffle plate and an annular base plate, the said baffle plate and the annular base plate constituting a means for maintaining the water and the dirt in the sediment collector in an unagitated state.

A further object is to provide a washing machine which is simple to operate, efficient in use and cheap to manufacture.

Other objects and advantages of the invention will be apparent during the course of the following description.

In the accompanying drawing forming a part of this application and in which like numerals are employed to designate like parts throughout the same,

Figure 1 is a vertical transverse sectional view through the washing machine constructed in accordance with this invention.

Figure 2 is a perspective of the baffle member and closure for the sediment collector detached.

In the drawing the numeral 5 designates a receptacle adapted for the reception of clothes to be washed by the action of an agitator 6 and a cleaning medium in the water.

As illustrated in Figure 1 the bottom 7 of the receptacle 5 is funnel-shaped or slopes toward the center of the receptacle and is provided with a depending integral cylindrical sediment receptacle or collector 8. The sediment collector 8 is preferably of cylindrical formation and is provided with a drain pipe 9 having a valve 10 by means of which sediment and the dirty water in the collector may be discharged.

The receptacle 5 is provided with a perforated tray 12 which constitutes a means for supporting the clothes above a combined

baffle and closure 13. The combined baffle and closure 13 is provided with an annular base plate 14 which flatly contacts with the funnel-shaped bottom 7 and extends for a substantial distance into the sediment collector 8 so as to prevent the operation of the agitator 6 from agitating the water and the dirt in the collector 8. That is to say the inner edge portion of the annular base plate 14 partly closes the upper end of the sediment collector 8 and therefore maintains the water and the dirt in the sediment collector in an unagitated state. The member 13 is provided with a depending cylindrical attaching flange 16 which is received within the collector 8 and is secured to the base plate between the inner and outer edges of the same.

A baffle plate or disk 18 is provided with a plurality of attaching arms 20 which extend downwardly and are secured to the upper side of the base plate 14. The baffle disk or plate 18 is supported in spaced relation to the base plate 14 and thereby provides an annular passage between the disk 18 and the plate 14 so that the water may pass from the receptacle 5 to the collector 8.

In operation the desired quantity of water and cleaning medium is placed in the machine and when the clothes are also arranged in the machine the agitator 6 is set in motion. As the agitator removes the dirt from the clothes the dirt drops down through the perforated tray 12 into the water in the collector 8. The dirt-laden water in the collector 8 is not subjected to the agitation to which the water in the receptacle 5 is subjected and therefore the dirt is allowed to settle. The dirt-laden water in the receptacle 5 passes downwardly between the baffle disk 18 and the base plate 14 and enters the collector 8. When desired the water may be drained off from the collector 8 by opening the valve 10. By removing the disk or tray 12 the combined baffle and closure 13 may also be removed so as to afford full access to the collector 8 for the purpose of thoroughly cleaning the same.

I claim:

1. A washing machine comprising a receptacle having a sloping bottom, provided with a depending integral sediment collector, and a combined baffle and closure seated on said bottom and having an annu-

lar base plate extended inwardly beyond the side wall of said sediment collector and constituting a means for partly closing the same, said combined baffle and closure also being provided with a baffle member arranged in spaced relation to said annular base plate.

2. A washing machine comprising a receptacle having a depending sediment collector, a combined baffle and closure having an annular base plate extended inwardly beyond the side wall of said sediment collector and constituting a means for partly closing the same, said combined baffle and closure also being provided with a baffle disk arranged in spaced relation to said annular base plate, and a perforated tray arranged within said receptacle above said combined baffle and closure.

20 3. A washing machine comprising a receptacle having a depending sediment collector, a combined baffle and closure seated on said bottom and having an annular base plate extended inwardly beyond the side wall of said sediment collector and constituting a means for partly closing the same,

said combined baffle and closure also being provided with a baffle disk arranged in spaced relation to said annular base plate, and a drain associated with said collector, 30 said combined closure and baffle being provided with a depending attaching member received in said collector.

4. A washing machine comprising a receptacle having a bottom wall and a depending sediment collector, a combined baffle and closure detachably arranged within said receptacle and having an annular base plate and a depending annular attaching plate secured to said base plate between its edges 40 and extending into said collector, said combined baffle and closure also being provided with a baffle disk arranged in spaced relation to said base plate, said annular base plate being extended inwardly beyond the 45 side wall of said collector and constituting a means for partly closing said collector, the inner edge of said annular base plate being arranged inwardly of the periphery of said disk.

HARRY WAYNE WHITE.
